DESIGN FOR A SULKY

Al B. White, Freeport, N. Y., assignor to Al B. White Manufacturing Co., Inc., Freeport, N. Y., a corporation of New York

Application October 22, 1946, Serial No. 134,174

Term of patent 14 years

(Cl. D14—3)

To all whom it may concern:

Be it known that I, Al B. White, a citizen of the United States, residing at Freeport, Long Island, in the county of Nassau and State of New York, have invented a new, original, and ornamental Design for a Sulky, of which the following is a specification, reference being had to the accompanying drawing, forming part thereof.

In the drawing:

Fig. 1 is a perspective view of a sulky showing my new design;

Fig. 2 is a side elevational view thereof.

The dominant features of my design reside in the portions shown in full lines.

I claim:

The ornamental design for a sulky, substantially as shown and described.

AL B. WHITE.
